TYPEWRITING MACHINE.

1,419,195.

Specification of Letters Patent. Patented June 13, 1922.

Application filed October 3, 1918. Serial No. 256,684.

To all whom it may concern:

Be it known that we, FRANK H. ARMSTRONG and EDWIN L. HARMON, citizens of the United States, and residents of Auburn, county of Cayuga, and State of New York, and of Groton, county of Tompkins, and State of New York, respectively, have invented certain new and useful Improvements in Typewriting Machines (Case 10 #146), of which the following is a specification.

This invention relates more particularly to line spacing means for visible typewriting machines.

One of the main objects of the invention is to provide simple and efficient means for line spacing the platen for typewriting machines, the spacing mechanism being so constructed that it serves to lock the platen 15 against rotation at the end of each line spacing movement to prevent overrunning of the platen, and to insure accurate spacing between the lines of typewriting.

Another object of the invention is to provide a line spacing means wherein the line spacing pawl in its normal or at-rest position will be out of engagement with the line space ratchet wheel, whereby the platen may be readily turned in either direction through 20 the finger pieces or knobs.

Another object of the invention is to provide simple and efficient means for varying the extent of the line spacing rotation of the platen.

A further object of the invention is to simplify and improve the line spacing mechanism, and to construct the mechanism of simple parts, which may be readily and accurately assembled.

In the drawings, Figure 1 is a plan view of one end of a platen carriage and platen, showing the line spacing mechanism in position;

Fig. 2 a front elevation of the parts shown 40 in Fig. 1;

Fig. 3 a vertical sectional view on the line III—III of Fig. 1, viewed in the direction indicated by the arrows;

Fig. 4 a detail sectional view, showing the 50 support of one end of the rocking yoke which carries the line space lever, the section being indicated by the dotted line IV—IV of Fig. 1;

Fig. 5 an end elevation of the platen carriage and the line spacing mechanism; 55

Fig. 6 a detail front elevation of the platen and line spacing mechanism, similar to Fig. 2, showing the line space lever at the completion of its line spacing movement;

Fig. 7 a detail view of the spring detent for holding the line space ratchet wheel;

Fig. 8 a detail sectional view of the line space lever showing the index device;

Fig. 9 a diagrammatic sectional view of 65 the ratchet wheel and the line space pawl in normal disengaged position;

Fig. 10 a diagrammatic plan view of the parts shown in Fig. 9;

Fig. 11 a diagrammatic sectional view 70 showing the line space pawl in engagement with the line space ratchet wheel; and

Fig. 12 a diagrammatic plan view of the parts shown in Fig. 11.

Referring to the various parts by numerals, 1 designates the left-hand end of the platen carriage; 2 the carriage end bracket, and 3 the platen suitably journaled in said bracket. The end of the platen shaft is provided with the usual finger piece or knob 4, 80 by which it may be freely rotated in either direction. Suitably secured to the platen end or to the platen shaft, as desired, is a line space ratchet wheel 5, having its teeth on the periphery thereof in the usual manner, as indicated in the drawings. 85

The end bracket 2 of the platen carriage is formed at its forward edge at a short distance above the carriage bed with an inwardly extending pivot bracket or lug 6, the 90 lower edge of said bracket being recessed at 6^a, for a purpose which will hereinafter appear. Pivoted at the right-hand end of the lug 6 is a line space lever 7, said lever being formed with the upwardly extending operating arm 8 and with the outwardly and downwardly extending arm 9. The line space lever near its point of pivot is provided with a rearwardly extending yoke 10, the inner end of which is bent upwardly and 100 inwardly to form the pivot arm 11, said inner arm being pivoted in an up-standing lug 13, formed on the carriage bed, as indicated clearly in Fig. 4. The said inner end of the pivoted yoke is formed with a depending lug 14, to which a spring 15 is con-

nected, the other end of said spring being secured to a suitable lug on the carriage bed. Said spring normally holds the line space lever in its normal position, as shown in Fig. 2, and returns it to that position after the line spacing operation. The operating arm 8 of the line space lever is provided at its upper end with a curved finger piece 16, which is adapted to be grasped when moving the line space lever to the right in the line spacing operation. The inner pivot of the yoke 10, which is also the inner support of the line space lever is formed by an integral bearing lug, preferably stamped out of the material forming the line space lever and the yoke 10, the said lug extending through a suitable aperture in the up-standing lug 13 of the carriage bed. It is manifest, however, that this pivot may be formed in any other suitable manner. It is manifest that by providing the yoke 10 and the inner bearing therefor, the line space lever is strengthened and supported in such manner that it will move accurately, and withstand a great amount of the necessarily rough usage which the line space lever is subjected to.

Pivoted to the lower end of the downwardly and outwardly extending arm 9 of the line space lever and on the inner side thereof is a line space pawl 17, said pawl normally extending upwardly and inwardly, the inner end thereof being turned outwardly and then downwardly to form a hook 18, adapted to embrace loosely the upper curved edge 19 of the line space lever, as indicated clearly in Figs. 1 and 2 of the drawings. Connected to the inner lower edge of the line space pawl and to the adjacent portion of the yoke 10 of the line space lever is a spring 19^a, said spring normally holding the line space pawl in its normal position against a stop pin 20, secured to the inner side of the line space lever. We preferably form this pin by stamping inwardly a portion of the said lever, but of course it may be formed in any other suitable manner. The stop pin 20 is adapted to engage the upper surface of the pivot lug 6 and to serve as a stop to limit the outward movement of the line space lever under the influence of its tension spring 15, as clearly indicated in Fig. 3 of the drawings, so that said pin serves as a stop for the line space lever and the line space pawl, and insures the accurate positioning of these parts with respect to the line space ratchet wheel. The outwardly turned hook 18 serves as an abutment to limit the movement of the pawl in the line space operation, as will be fully hereinafter described. The line space pawl is provided on its upper surface, substantially midway its ends, with a rearwardly extending, substantially horizontal, tooth-engaging portion or nose 21, whose inner end is stepped to form an abutment 22,

adapted to be brought into engagement with the outer vertical, flat surface of the ratchet wheel, the leading edge of the main part of the nose 21 being close to the side of said ratchet wheel, and in a position to be brought into engagement with the teeth thereof through the movement of the line space lever.

Pivoted to the line space lever on the pivot screw 23, which connects the line space pawl to said lever, is the lower end of an index device or arm 24, said index device lying close to the inner side of the line space lever, and between said lever and the line space pawl. The index device is formed of thin spring metal, and extends upwardly from its pivot, the upper end thereof being bent forwardly and extending through an arc-shaped slot 25, formed in the line space lever, as clearly shown in Fig. 2 of the drawings. The extreme upper end of the index device is then bent upwardly to form the finger piece 26, which lies on the forward side of the lever in convenient position to be engaged by the operator. The index device just below the finger piece, is formed

with a forwardly extending locking lug 27, which is adapted to engage any one of the three index notches 28, formed in the lower margin of the slot 25 in the line space lever. The forwardly extending, substantially horizontal part 29 of the index device, which carries the finger piece 26 at its forward end, serves as a limiting abutment or stop, and is adapted to be engaged by the abutment hook 18 of the line space pawl. The index notches 28, are so placed with respect to the at-rest position of the line space pawl, that the abutment 18 will engage the stop 29, when the line space pawl has engaged and moved the ratchet wheel the desired number of spaces. The index device is of resilient metal, so that the locking lug 27 may be released from the index notches by pressing inwardly the finger piece 26. When the index device is in register with the desired index notch, the finger piece 26 is released, whereupon the index device will spring forwardly to bring its locking lug into engagement with the registering index notch. The index device is so mounted on its pivot that when released it may be freely swung to the desired index notch.

It is thought that the operation of the device is manifest from the foregoing description, but it may be briefly stated as follows:

By placing the locking lug of the index device in the innermost index notch (a) the abutment 29 will be brought close to the abutment 18 of the line space pawl. The parts will then be in position to give the platen a movement of one tooth of the line space ratchet wheel. A complete movement of the line space lever to the right will first cause the nose 21 to enter between two teeth

of the line space wheel, the shoulder 22 engaging the vertical outer side of said wheel. The continued movement of the line space lever will cause the line space pawl to rotate the ratchet wheel until the abutment 18 and the stop 19 contact, the two abutments approaching each other during the movement of the line space lever. When the ratchet-wheel has thus been rotated the pre-10 determined distance, the continued pressure on the line-space lever causes the projection 22 on the line-space pawl to jam hard against the non-toothed face of the ratchet-wheel to thus cause a braking action on the 15 ratchet-wheel thereby preventing overthrow, no matter how sharply the line-space lever may be operated. Upon the release of the line space lever the spring 15 will return it to its normal position, the stop pin 20 20 engaging the upper edge of the pivot lug 6. The spring 19 will return the line space pawl to its normal position against said stop 20.

By placing the locking lug of the index 25 device in the index notch marked *b*, the movement of the line space pawl will be sufficient to rotate the platen the distance of two ratchet teeth; and by placing it in the index notch marked *c*, the distance between 30 the abutments 18 and 29 will be sufficient to cause the pawl to rotate the platen the distance of three teeth before said abutments engage each other.

Figs. 11 and 12 show the position of the 35 nose of the line space pawl when it is in engagement with the ratchet wheel, and Figs. 9 and 10 show the normal position of the nose of the line space pawl when it is free of the ratchet wheel.

40 A spring-pressed roller 30 is mounted on the carriage and engages the ratchet teeth to prevent the accidental rotation of the platen when the line space pawl is free of the ratchet wheel. It is manifest however, 45 that the platen may be rotated by grasping the finger pieces 4, the roller 30 yielding to permit this operation.

The pivot lug 6 is recessed at 6^a to permit the horizontal bar of the yoke 10 to swing 50 upwardly when the line space lever is moved in the line spacing operation.

The finger piece 26 is bent rearwardly toward the line space lever and serves as a stop to engage the forward face of said lever and 55 thereby limit the inward movement of the resilient index device. The stop is so located that when it is in engagement with the face of the line space lever, the locking lug 27 will be freed from the index notches and 60 the index device may then be swung freely on its pivot.

What we claim is:—

1. In a typewriting machine, the combination of a platen frame, a rotary platen 65 therein, a line space ratchet wheel connected

to said platen, a line space lever pivoted on said frame, a line space pawl pivoted on the lever and provided with a nose adapted to engage the ratchet wheel, a flexible index device mounted on the pivot of the line space 70 pawl and adapted to be moved toward or from the line space pawl, an abutment formed on said index device and extending through a segmental slot formed in the line space lever, a lug on said index device adapted to engage index notches formed in the line space lever, said abutment being adapted to engage the line space pawl at the completion of the line spacing operation. 75

2. In a typewriting machine, the combination of a platen frame, a rotary platen therein, a line space ratchet wheel connected to said platen, a line space lever pivoted on said frame, a line space pawl pivoted on the lever and provided with a nose adapted to 80 engage the ratchet wheel, a flexible resilient index device mounted on the pivot of the line space pawl, its free, outer end being adapted to be swung toward or from the outer end of the line space pawl, the upper 85 end of said index device extending forwardly through a segmental slot in the line space lever, and forming an abutment, a locking lug formed on said index device and adapted to engage any one of a series of index notches in the line space lever, an abutment formed on the outer end of the line space pawl and adapted to be brought into 90 engagement with the abutment on the index device when the nose of the line space pawl 95 is in engagement with the teeth of the ratchet wheel, and a finger piece formed on the index device whereby said locking lug may be snapped into any one of the index notches and the abutment on said device 100 shifted in its relation to the abutment on the line space pawl.

3. In a typewriting machine, the combination of a platen frame, a rotary platen therein, a line space ratchet wheel connected to 110 said platen, a line space lever pivoted on said frame, a line space pawl pivoted on the lever and provided with a nose adapted to engage the ratchet wheel, a flexible resilient index device mounted on the pivot of the 115 line space pawl, its free outer end being adapted to be swung toward or from the outer end of the line space pawl, the upper end of said index device extending forwardly through a segmental slot in the line 120 space lever and forming an abutment, a locking lug formed on said index device and adapted to engage any one of a series of index notches in the line space lever, an abutment formed on the outer end of the line 125 space pawl and adapted to be brought into engagement with the abutment on the index device when the nose of the line space pawl is in engagement with the teeth of the ratchet wheel, a finger piece formed on the 130

index device whereby the locking lug may be snapped into any one of the index notches and the abutment on said device shifted in its relation to the abutment on the line space 5 pawl, a spring connected to the line space lever to return it to its normal position, a stop to arrest the line space lever in its normal position, and a spring connected to the line space pawl and to the line space lever 10 to return said pawl to its normal position against the line space lever stop.

4. In a typewriting machine, the combination of a platen frame, a rotary platen therein, a line space ratchet wheel connected to 15 said platen, a line space lever pivoted on said frame, a line space pawl pivoted on the lever and provided with a nose adapted to engage the ratchet wheel, a flexible resilient index device mounted on the pivot of the 20 line space pawl on the inner side of the line space lever, a forwardly extending abutment formed on the upper end of the index device and extending forwardly through a segmental slot in the line space lever, a finger piece on the forward end of said abutment, a forwardly extending locking lug formed on said index device and adapted to engage any one of a series of index notches 25 in the line space lever, an abutment formed on the outer end of the line space pawl and adapted to be brought into engagement with the abutment on the index device as the line space lever is moved for the line spacing 30 operation, a spring to return the line space lever to its normal position, a spring to return the line space pawl to its normal position, and a common stop to limit the movement of the line space lever and the line 35 space pawl.

40 5. In a typewriting machine, the combination of a platen carriage, a platen rotatably supported on the carriage, a ratchet wheel rotatable with the platen, a line space lever pivotally supported on the carriage, a laterally flexible index device pivotally held to the lever at one side of the lever and having a finger piece normally spaced from and adapted to engage the opposite side of said lever to limit the flexure of said device, 45 operating means on said device and lever for locking the device in different pivotally adjusted positions releasable by flexure of said device, and a pawl pivotally held to the lever for rotating the ratchet wheel and 50 rockable into engagement with said index device to limit the throw of the lever and pawl.

55 6. In a typewriting machine, the combination of a platen frame, a rotary platen therein, a line space ratchet wheel connected to 60 said platen, a line space lever pivoted on said frame, a line space pawl pivoted on the lever and provided with a nose adapted to engage the ratchet wheel, an index device 65 mounted on the pivot of the line space pawl

and adapted to be moved at its outer end toward or from the outer end of the line space pawl, an abutment formed on said index device, a lug on said index device adapted to engage any one of a series of index notches 70 formed in the line space lever, an abutment on the line space pawl adapted to engage the abutment on the index device to limit the movement of the line space pawl in its line spacing operation, a spring to return 75 the line space lever to its normal position, a spring to return the line space pawl to its normal position, and a common stop to arrest the line space lever and the line space pawl in their normal positions. 80

7. In a typewriting machine, the combination of a platen carriage, a platen rotatably supported on the carriage, a ratchet wheel rotatable with the platen, a line space lever pivotally supported on the carriage, a pawl pivotally held to the line space lever adapted to engage and rotate the ratchet wheel when the lever is rocked in one direction, a stop on the carriage, and a stop on the lever cooperating with the stop on the 90 carriage to determine the normal position of the lever and adapted to move the pawl out of engagement with the ratchet wheel as the lever returns to normal position.

8. In a typewriting machine, the combination of a platen carriage, a platen rotatably supported on the carriage, a ratchet wheel rotatable with the platen, a line space lever pivotally supported on the carriage, a pawl pivotally held to the line space lever adapted to engage and rotate the ratchet wheel when the lever is rocked in one direction, a spring for normally rocking the lever in the opposite direction, cooperating stops on the lever and carriage for determining the normal position of the lever, and a spring for normally rocking the pawl into engagement with the stop on the lever, said stop on the lever being so located as to cause the pawl to rock with the lever out of engagement with the ratchet 105 wheel as the lever returns to normal position. 110

9. In a typewriting machine, the combination of a platen frame, a platen, a line space ratchet wheel, a line space lever pivoted on said frame, a line space pawl pivoted on the lever and adapted to engage the ratchet wheel, a flexible resilient index device pivoted on the line space lever and adapted to be moved toward or from the line space 115 pawl, an abutment formed on said index device and extending through a slot formed in the line space lever, a lug on said index device adapted to engage index notches in the line space lever, said abutment being adapted to engage the line space pawl at the completion of the line spacing operation. 120

10. In a typewriting machine, the combination of a line space lever pivotally supported, a line space pawl pivoted on the said lever, a flexible resilient index device pivoted 125 130

on the line space lever, the upper end of said index device extending through a slot in the line space lever and forming an abutment, a locking lug on said index device adapted to engage any one of a series of index notches in the line space lever, an abutment formed on the outer end of the line space pawl adapted to be brought into engagement with the abutment on the index device at the completion of the line spacing operation, and a finger piece formed on the index device, whereby said locking lug may be snapped into any one of the index notches and the abutment on said device shifted in its relation to the abutment on the line space pawl.

11. In a typewriting machine, the combination of a platen carriage, a platen rotatably supported on the carriage, a ratchet wheel rotatable with the platen, a line space lever pivotally supported on the carriage, a pawl pivotally held to the line space lever adapted to engage and rotate the ratchet wheel when the lever is rocked in one direction, a stop on the carriage, a stop on the lever cooperating with the stop on the carriage to determine the normal position of the lever and adapted to move the pawl out of engagement with the ratchet wheel as the lever returns to normal position, and an adjustable stop on the lever cooperating with the pawl for determining the extent of pivotal movement of the pawl relatively to the lever.

12. In a typewriting machine, the combination of a line space lever pivotally supported, a line space pawl pivoted on the said lever, a flexible resilient index device pivoted on the line space lever the upper end of said index device extending through a slot in the line space lever and forming an abutment, a locking lug on said index device adapted to engage any one of a series of index notches in the line space lever, an abutment formed on the outer end of the line space pawl adapted to be brought into engagement with the abutment on the index device at the completion of the line spacing operation, a finger piece formed on the index device whereby said locking lug may be snapped into any one of the index notches and the abutment on said device shifted in its relation to the abutment on the line space pawl, and a stop carried by the index device and adapted to engage the line space lever when the locking lug has been forced out of the index notches.

13. In a typewriting machine, the combination of a platen carriage, a platen rotatably supported on the carriage, a ratchet wheel rotatable with the platen, a line space lever pivotally supported on the carriage to

swing transversely of the ratchet wheel, a pawl pivotally held to the lever to swing in a plane at right angles to the ratchet wheel about a different axis from the pivotal axis of the lever, adjustable and fixed stops on the lever cooperating with the pawl for determining the extent of movement of the pawl about its pivot, an abutment on the carriage cooperating with the fixed stop on the lever for determining the normal position of the lever, and yieldable means for restoring the lever to normal position.

14. In a typewriting machine, the combination of a platen carriage, a platen rotatably supported on the carriage, a ratchet wheel rotatable with the platen, a line space lever pivotally supported on the carriage to swing transversely of the ratchet wheel, a pawl pivotally held to the lever to swing in a plane at right angles to the ratchet wheel about a different axis from the pivotal axis of the lever, cooperating fixed stops on the lever and carriage for determining the normal position of the lever, a spring for restoring the lever to normal position, a resilient arm pivotally held at one end to the lever and provided with an abutment cooperating with the fixed stop on the lever to determine the extent of movement of the pawl about its pivot, cooperating means on the arm and lever for locking the free end of the arm to the lever in different pivotally adjusted positions, and a finger piece on said arm for flexing the arm laterally to release the free end of the same from the lever.

15. In a typewriting machine, the combination of a platen carriage, a platen journaled in the carriage, a ratchet wheel rotatable with the platen, a line space lever provided with a pivot yoke extending transversely of the carriage, means pivotally connecting the yoke at its ends with the carriage to permit the lever to be rocked in a plane at right angles to the ratchet wheel, a line-space pawl pivotally held to the lever at a point at one side of the yoke, a fixed stop on the lever above the yoke, a spring connected with the pawl and yoke normally holding the pawl against said fixed stop, an adjustable stop on the lever cooperating with said pawl to limit the extent of movement of the pawl about its pivot, an abutment on the carriage cooperating with the fixed stop on the lever to determine the normal position of the lever, and yieldable means for restoring the lever to normal position.

This specification signed this 24th day of September, 1918.

FRANK HURBERT ARMSTRONG.
E. L. HARMON.
